UNITED STATES PATENT OFFICE.

JACOB BRAUDE, OF NEW YORK, N. Y.

ATTACHMENT FOR SEWING-MACHINES.

1,287,205.

Specification of Letters Patent. Patented Dec. 10, 1918.

Application filed December 22, 1917. Serial No. 208,509.

To all whom it may concern:

Be it known that I, JACOB BRAUDE, a citizen of the United States, residing at New York, in the county of New York, 5 city and State of New York, have invented certain new and useful Improvements in Attachments for Sewing-Machines, of which the following is a specification.

My invention relates to attachments for 10 sewing machines which are intended to be used for sewing on a border of lace or the like to a piece of material.

In various classes of needle work of the finer grades it is necessary to sew a border 15 or edge of fine material such as lace or braid or the like, to a garment or other article such as handkerchiefs, etc.

Numerous devices for this purpose have 20 been proposed heretofore, but they either required the construction of an entirely new sewing machine, or proved unsatisfactory. The average small plant found it too expensive to purchase special machines for the sole purpose of sewing on borders, and even 25 in the larger plants it was very inconvenient to take the completed garments or articles from the operators who had sewed them, to the special machines which were to sew on the borders or edges. Additional complications in the adjustment of wages, etc., 30 made these special machines further undesirable.

My invention is directed toward providing 35 a simple attachment in the form of a special work plate which can be applied to various well-known types of machines, which can be readily inserted and removed and which shall be reliable in operation, and not tear or injure the delicate fabrics to 40 which the border or edging is to be applied. Since this little attachment can be put into place almost instantly, the regular operator 45 who has made the garment or the like can sew on the borders or edges, and this would be especially convenient in small plants.

Other objects of my invention will be pointed out in the following description and drawings which illustrate a preferred embodiment of my invention.

50 Figure 1 is a perspective view of a portion of a sewing machine showing my improved device in position.

Fig. 2 is a top view of my attachment showing the dogs.

55 Fig. 3 is a cross section along the line 3—3 in the direction of the arrow.

Fig. 4 is a cross section along the line 4—4 in the direction of the arrow.

Fig. 5 is a cross section along the line 5—5 in the direction of the arrow. 60

Fig. 6 is an enlarged perspective view showing the connection between the border and the fabric.

The attachment consists of a work plate 1 having suitable openings 2 and 3 into 65 which suitable screws can be inserted for connecting the attachment to the machine.

The attachment has slots 4, 5 and 6 in which three feed dogs of the ordinary and well-known type can operate. These feed 70 dogs 7 and 8 of the ordinary and well-known type may be operated by any of the ordinary and well-known movements, and they are not further illustrated because in themselves they form no part of my invention and are 75 within the comprehension of any person skilled in the art. The feed dog 20 is of a similar type.

A bifurcated presser foot 9 is provided 80 which is also operated by means of ordinary and well-known connections, and as these are within the comprehension of any person skilled in the art, they do not require further illustration, and this statement also applies to various other connections and the like, 85 which are not shown in the drawings.

The needle 10, connected to the needle bar 11, operates in the transverse slot 12, so as to give a zig-zag stitch. At one stroke the needle operates at the left hand end of the 90 slot 12, and at the other at the right hand side of this slot, the tension and take-up being of the well-known type. The attachment is provided with a groove 13 which commences very close to the slot 4, 95 about 1/64 of an inch away therefrom, and ends at the slot 12 at about 1/3 of the distance from the right hand thereof. This groove 13 has a little extension 14, which is substantially parallel to the slot 4. This 100 extension 14 is of uniformly varying depth, having its greatest depth at its junction with slot 13, and being of zero depth at its other end.

For the first third of its length, the groove 105 13 is provided with a tongue 15. For the first third of its length the parallel side walls of the groove 13 are inclined about 30 degrees to the horizontal, as shown in Fig. 5. For the next third these walls are substantially perpendicular, and for the last third they are inclined 45 degrees to the ver-

tical in an opposite direction to that shown in Fig. 5. The junctions of the three portions of the groove 13 may be made gradual if desired, and the change of inclination 5 may also be made uniform throughout the entire groove starting from an inclination of 30 degrees on one side of the horizontal to an inclination of 45 degrees to the other side of the horizontal.

- 10 The attachment is also provided with a tongue 15 as before mentioned, whose walls are substantially parallel to the adjacent walls of the groove 13 and have the same inclination to the horizontal, and which 15 has an overhanging horizontal portion about 1/16 of an inch in length.

The operation of my device is as follows:

- The operator advances the fabric of the article 16, until its edge touches the extension 20 14 of the groove 13. The tongue 15 acts as a guide, so that when the fabric is further advanced, it enters the groove 13, and is inclined at an angle of between 30 degrees to 45 degrees to the slots 4 and 5. 25 The groove 13, because of its configuration causes the fabric to be bent over, the amount of fabric bent over being dependent upon the depth of the groove. The fabric is thus fed forward by the dog 8 in front of the 30 needle, and is also fed forward by the left hand part of the dog operating in slot 6, behind the needle. The lace or other edging is introduced just under the needle, and so as to overlap the doubled edge of the fabric, 35 at the other side of tongue 15, which acts as a guide. The lace is fed by the dogs 20 and 7.

- I prefer to apply this attachment to that type of machine known as the Singer 107 w 1, 40 zig-zag stitch type.

- The edge of the tongue 15 which is opposite the slot 13 and which is parallel to the direction thereof, assists the operator in placing the fabric so that it is properly fed. 45 The transverse movement of the needle bar 11, that is, the transverse distance between consecutive stitches, is such that alternate stitches penetrate the fabric and the lace just over the doubled-over edge, and 50 the intermediate stitches penetrate the fabric a short distance away from the edge of the lace. If desired, the outer stitches can just pass the doubled or folded edge of the fabric as shown in Fig. 6. The depth of the 55 groove is dependent upon the thickness of the fabric, which must be folded over sufficiently so as to permit the sewing together shown in Fig. 6.

- The edge of the fabric which has been 60 doubled over to an angle of 45 degrees is drawn closely against the body of the fabric as shown in Fig. 6, by the action of the take-up of the sewing machine which tightens the thread so that the edging shown 65 in Fig. 6 is produced.

Although any form of stitch may be used, I prefer the lock stitch.

Once the materials have been properly set in by the operator, the action of the machine is almost automatic, as the fabric of the article 16 is fed forward by the dog 8 and by a part of the dog in the slot 6, and the lace is fed by the remaining part of the dog in the slot 6 and is also fed to a certain extent by the dog in slot 4, if desired. 75

I prefer to attach the bottom of the presser foot to the shank thereof so that there is a limited rotary movement along the line 17.

I have shown a preferred embodiment of 80 my invention but it can be applied to other machines besides the one above mentioned, and numerous changes and omissions can be made without departing from its spirit. 85

I claim:

1. A work-plate having three parallel slots, the front of the middle slot being spaced from the fronts of the said other slots, so that a space is left in front of the said middle slot and between the said other slots, the said slots being adapted to receive feed dogs, a needle-hole being located in front of the said middle slot and between the said other slots, and a groove intermediate the said other slots and in front of the said needle-hole, the said groove being adapted to receive the edge of a piece of fabric, the rear walls of the said groove being inclined to the vertical, so as to double over the said edge of the fabric with respect 100 to the body thereof.

2. A work-plate having three parallel slots, the front of the middle slot being spaced from the fronts of the said other slots, so that a space is left in front of the 105 said middle slot and between the said other slots, the said slots being adapted to receive feed dogs, a needle-hole being located in front of the said middle slot and between the said other slots, and a groove intermediate the said other slots and in front of the said needle-hole, the said groove being adapted to receive the edge of a piece of fabric, the rear walls of the said groove being inclined to the vertical, so as to double over the said edge of the fabric with respect 110 to the body thereof, the said groove running at an angle to the said slots.

3. A work-plate having three parallel slots, the front of the middle slot being 120 spaced from the fronts of the said other slots, so that a space is left in front of the said middle slot and between the said other slots, the said slots being adapted to receive feed dogs, a needle-hole being located in 125 front of the said middle slot and between the said other slots, and a groove intermediate the said other slots and in front of the said needle-hole, the said groove being adapted to receive the edge of a piece of 130 fabric.

fabric, the rear walls of the said groove being inclined to the vertical, so as to double over the said edge of the fabric with respect to the body thereof, the said groove running at an angle to the said slots, and beginning substantially at the adjacent edge of one of said slots.

4. A work-plate having three parallel slots, the front of the middle slot being spaced from the fronts of the said other slots, so that a space is left in front of the said middle slot and between the said other slots, the said slots being adapted to receive feed dogs, a needle-hole being located in front of the said middle slot and between the said other slots, and a groove intermediate the said other slots and in front of the said needle-hole, the said groove being adapted to receive the edge of a piece of fabric, the rear walls of the said groove being inclined to the vertical, so as to double over the said edge of the fabric with respect to the body thereof, the said groove running at an angle to the said slots, and beginning substantially at the adjacent wall of one of said slots, and terminating at the said needle-hole at $\frac{1}{2}$ the distance from the right hand end of said needle-hole.

5. In a sewing machine, a work-plate having a groove for folding over fabric, the front of said groove having its walls inclined to the horizontal, and the rear of said groove having its walls inclined in the opposite direction to the horizontal.

35 6. In a sewing machine, a work-plate having a groove for folding over fabric, the

front of said groove having its walls inclined to the horizontal, and the rear of said groove having its walls inclined in the opposite direction to the horizontal, the said work-plate also having a tongue adjacent the front portion of said groove, the said tongue having walls inclined at the same angle as the adjacent walls of the groove.

7. In a sewing machine, the combination of parallel feeding means, stitching mechanism including a needle, capable of being moved up and down and also in a lateral path to produce a zig-zag stitch, the said feeding means being located at opposite sides of the said lateral path, and means for folding over a piece of fabric, said folding means being located in front of the needle and intermediate said feeding means.

8. In a sewing machine, the combination of a work-plate having a needle slot; stitching mechanism including a needle, capable of being moved up and down and from side to side to produce a zig-zag stitch, means for folding the edge of a piece of fabric located in front of said needle and terminating intermediate the ends of said slot, and means for feeding said folded fabric, and an edging to said mechanism so that the folded fabric and the edging are fed across said slot intermediate the ends thereof, and a series of alternate stitches pass through said fabric, and the other alternate stitches pass through the edging only.

In testimony whereof I hereunto affix my signature.

JACOB BRAUDE.
